UNITED STATES PATENT OFFICE.

DAVID L. DE GOLYER, OF CHICAGO, ILLINOIS.

IMPROVEMENT IN WOOD PAVEMENTS.

Specification forming part of Letters Patent No. 97,278, dated November 30, 1869.

To all whom it may concern:

Be it known that I, DAVID L. DE GOLYER, of Chicago, in the county of Cook and State of Illinois, have invented a new and useful Improvement in Wooden Pavements; and I do hereby declare that the following is a full, clear, and exact description thereof.

The nature of my invention consists in the construction of a wooden-block pavement, by setting blocks of prepared wood, saturated with any known composition or material to prevent rot or decay, endwise upon the roadway, on a proper foundation for support, with spaces, interstices, or cells between said blocks, filled with self-cementing gravel or broken stone, containing a proper proportion of lime, as hereinafter specified, without the admixture of tar, pitch, or any artificial cement.

Heretofore, in all wooden pavements constructed by setting blocks of wood on end, with spaces, interstices, or cells between them, said spaces, interstices, or cells have been filled with gravel or broken stone, intermixed with tar, or some similar pitchy matter; but it has been found by experiment that the tar or other pitchy matter so used has a tendency to cause dry-rot in the wooden blocks, commencing in the central portion thereof, and this has proved to be a very serious defect in all wooden pavements now in common use.

In order to remedy this defect, I prepare my blocks of wood, before setting them in the pavement, according to the process described in Letters Patent issued to John L. Samuels, bearing date the 1st day of January, 1867, No. 60,794; or saturate them with any known material, or by any known process, to prevent the wood from decaying, and I fill the spaces, interstices, or cells between them with self-cementing gravel or broken stone, unmixed with tar or any other pitchy matter or artificial cement.

I set my prepared blocks of wood upon a proper foundation for support, in any of the known modes of setting them in a pavement, so as to leave spaces, interstices, or cells between them to be filled with gravel, broken stone, or similar filling, said spaces, interstices, or cells extending from the surface clear down to the foundation, or only a part of the way down.

It is well known to persons having experi-

ence in the construction of macadamized or gravel roads, that gravel containing a considerable quantity of lime, or broken limestone, or other broken stone, intermixed with limestone-gravel, will, under travel, soon become cemented so as to form a water-tight covering, without the intermixture of any artificial cement. Such self-cementing gravel will often be found in gravel-banks suitable for use as taken from the bank, and will be readily recognized by any one having experience in the construction of gravel turnpikes. It should be free from loam, and not contain much clay; but a proper proportion of sand will not be injurious. In fact, any self-cementing gravel suitable for making a good gravel turnpike will answer the purpose.

I fill the spaces, interstices, or cells between the wooden blocks with self-cementing gravel or broken stone, as above described, and then cover the surface of the pavement all over with said self-cementing gravel to the depth of about two inches, which covering should remain thereon from one to three months.

When the blocks of wood have been saturated with any suitable material for preventing rot or decay, the use of tar or any similar pitchy material intermixed with the gravel or broken stone will be an absolute injury, as it will tend to produce dry-rot in the wood, and, furthermore, tar will not adhere to wood thus prepared.

I do not claim any new mode of setting wooden blocks in a pavement; nor do I claim, broadly, filling the spaces, interstices, or cells between the blocks with clean gravel or broken stone; but

What I do claim as my invention, and desire to secure by Letters Patent, is—

A pavement composed of wooden blocks saturated with any known material and by any known process for preventing rot or decay, set on end upon a proper foundation, with spaces, interstices, or cells between them filled with self-cementing gravel or broken stone, as above described, without the admixture of tar or any other pitchy matter or artificial cement.

DAVID L. DE GOLYER.
